YARN TAKE-OFF AND TENSION MEANS

Peleg B. Briggs, Mystic, Conn., assignor to The Atwood Machine Company, Stonington, Conn., a corporation of Connecticut

Application March 11, 1940, Serial No. 323,393

6 Claims. (Cl. 242—150)

This invention relates to textile machines and more particularly to a yarn take-off and tension means for a doubling and twisting machine.

An object of the invention is to provide a simple, inexpensive and easily adjusted tension device and take-off for the over end delivery of strands of yarn to the twisting or other operating elements of a textile machine.

Another object of the invention is to provide guiding means for individual strands in a textile machine comprising loops formed at the opposite ends of a wire, the central portion of the wire being bent or coiled about a supporting post or rod to resiliently and frictionally retain the guiding means in position thereon.

And finally it is an object to provide a clamp engaging the ends of the bent wire forming the guiding members to retain these ends at a predetermined angle to each other and also to tightly clamp the bent or coiled portion of the wire about the supporting rod.

One feature which enables the above objects to be accomplished is that the tensioning means in the form of discs may rest upon the upper part of the clamping member for the wire forming the guiding means or directly upon the wire, the discs being oppositely disposed so that the strand may pass between them and partially about the supporting rod or preferably about a sleeve surrounding the rod, the tension applied to the strand being extremely light and being adjustable by varying the weight of the upper disc.

With the above and other objects in view the invention includes the features of construction and operation set forth in the following specification and illustrated in the accompanying drawing.

In the accompanying drawing annexed hereto and forming a part of this specification I have shown the invention embodied in a standard form of spool support or creel for a doubling and twisting machine, but it will be understood that the invention can be otherwise embodied and that the drawing is not to be construed as defining or limiting the scope of the invention, the claims appended to this specification being relied upon for that purpose.

In the drawing:

Fig. 1 is a side elevation of a part of a doubling and twisting machine showing the present invention applied thereto.

Fig. 2 is a front elevation of the parts shown in Fig. 1.

Fig. 3 is a plan view on a reduced scale of the

strand guiding and tensioning means shown in Figs. 1 and 2;

Fig. 4 is an enlarged view in elevation, parts being broken away to more clearly show their construction; and

Fig. 5 is an elevation of the take-off and tensioning means as seen from the right hand side of Fig. 4.

In the above mentioned drawing there has been shown but one embodiment of the invention which is now deemed preferable, but it is to be understood that changes and modifications may be made within the scope of the appended claims without departing from the spirit of the invention.

Briefly, and in its preferred aspect, the invention may include the following principal parts: first, a substantially vertical rod or post disposed in front of each vertical row of spools from which the strands are to be delivered; second, coiled wires closely contacting this rod or post so that they are frictionally retained in any position thereon, and there being as many coiled wires as there are delivery spools; third, thread guiding loops or eyelets at the opposite extended free ends of each of the wires; fourth, discs supported on the individual wires so that a strand being delivered from a spool may pass between the discs and partially about the vertical rod as it passes from its spool and from one guiding loop or eyelet to the opposite loop or eyelet on the opposite ends of a wire; fifth, a clamping member engaging over the opposite end portions of the coiled wires to hold these end portions at the proper or any predetermined angle to each other and to firmly tighten the coiled portion of the wires frictionally against the vertical rod or post; and sixth, a felt or other member on the upper surface of the clamping member upon which the lower disc rests.

Referring more in detail to the figures of the drawing there is provided a delivery spool support in the form of a frame 10 having spaced pins 11 outstanding therefrom upon which the spools 12 are mounted. In the drawing but one vertical row of spools 12 is indicated but it will be understood that there will be a plurality of similarly supported vertical rows of spools in any machine to which the invention may be applied.

Directly in front of each row of spools 12 is a supporting bar or rod 13. The lower end of this bar or rod 13 may be attached as shown in Figs. 1 and 2 to the support 10 and the upper end similar or in any other preferred manner attached to the support 10 or to an intermediate

bracket member (not shown). On the rod 13 and disposed substantially in front of each spool 12 is a take-off and tensioning means presently to be more fully described and which forms the principal part of the invention. Each of these means include as their guiding means loops or eyelets 14 and 15 respectively at the opposite and extended free ends of a coiled wire 16. In the drawing the loop 14 is formed by suitably bending one end of the wire 16 and the other end of the wire 16 has applied thereto a porcelain eyelet 15. The loop 14 is disposed in a position to guide a strand from a spool 12 to tension discs 17 and 18 on the bar 13 and the eyelet 15 guides the strand after passing between the discs 17 and 18 and as it passes to a drop wire 19.

The discs 17 and 18 referred to above are dished as shown most clearly in Fig. 4 and are oppositely disposed. Their central opening is large enough to permit them to pass over the rod 13 and over a sleeve 20 of wear resisting material, also slideable over rod 13. To place a slight drag on the discs 17 and 18 so that a slight but appreciable tension will be placed on the strands the lower disc 17 rests on a pad 21 of felt or other fibrous material. This pad 21 may be of ring form and fit within the concaved portion of disc 17. The pad 21 may rest directly upon the upper end of the coiled portion of wire 16 but preferably and as shown in the drawing rests upon a clamp member 22 and holds the disc 17 slightly spaced therefrom.

Clamp member 22 fits slidably over the rod 13 and forms a small platform for the pad 21. This portion of the clamping member is plane and is disposed substantially horizontally and maintains the discs 17 and 18 in their proper relative positions to their sleeve 20. From this central portion of the member 22 extend two downwardly extending clamping arms 23 and 24. Arm 23 clamps around the end of wire 16 upon which eyelet 15 is secured and arm 24 extends around or clamps the arm provided with the loop 14. As the arms 23 and 24 are integral with the central portion of the clamping member 22 the angle between the arms of wire 16 carrying the guiding members 14 and 15 can be controlled so that the guiding loop 14 and the eyelet 15 can be positioned at any proper relative angles to each other for the particular disposition and guiding of the strands called for by the machine on which they are mounted.

In addition to positioning the guide carrying arms of wire 16 at their proper angles the clamp 22 serves to bind the coils of the wire 16 more tightly against the rod 13 to firmly hold the complete assembly frictionally thereon. To change the position of the assembly up or down on the rod 13 it is only necessary to release the clamp arms 23 and 24 of member 22 from the ends of wire 16, separate these ends slightly manually to slightly enlarge the opening within the coiled portion, and then slide the coil 16 to the desired vertical position. After the clamp 22 is replaced in position the coil 16 will again firmly and resiliently engage the rod 13.

I claim as my invention:

1. A take-off and tension device for textile machines comprising in combination, a supporting rod, spaced wires having a connecting portion coiled about and frictionally engaging said rod to support said wires in adjusted positions thereon, strand guiding means at the opposite extended ends of said wires, and tensioning means for said strands supported in position by said coiled wires.

2. A take-off and tension device for textile machines comprising in combination, a supporting rod, spaced wires having a connecting portion coiled about and frictionally engaging said rod, strand guiding means at opposite extended ends of said wires, clamping means engaging said ends and retaining said ends in predetermined angular relation to each other, and tensioning means for said strands supported in position by said coiled wires and resting on said clamping means.

3. A take-off and tension device for textile machines comprising in combination, a supporting rod, spaced wires having a connecting portion coiled about and frictionally engaging said rod, strand guiding means positioned at the opposite extended ends of said wires, a clamping member mounted on said rod and having portions engaging and retaining said extended ends in predetermined angular relation to each other, and tensioning means for said strands supported in position on said clamping member.

4. A take-off and tension device for textile machines comprising in combination, a supporting rod, spaced wires having a connecting portion coiled about and frictionally engaging said rod, means to frictionally retain said wires in any position on said rod, pairs of opposed discs supported on said wires between which strands may pass, and means to frictionally retard rotation of said discs.

5. A take-off and tension device for textile machines comprising in combination, a supporting rod, spaced wires having a connecting portion coiled about and frictionally engaging said rod, a clamp member having depending arms engaging the opposite extended ends of each of said wires to frictionally retain said wires in any adjusted positions on said rod, a felt pad resting on each of said clamp members, and tensioning discs in pairs mounted on said rod and resting on said pad.

6. A take-off and tension device for textile machines comprising in combination, a supporting rod, spaced wires having a connecting portion coiled about and frictionally engaging said rod, a flat clamping member fitting over said rod and having portions engaging over the opposite ends of said wires and retaining said ends in predetermined angular relation to each other, strand guiding means at the extremities of said ends, felt pads resting on said clamping members, and opposed discs in pairs resting on said pads, whereby strands guided between said discs will be tensioned by the weight of one of said discs and the resistance to rotation thereof.

PELEG B. BRIGGS.
